UNITED STATES PATENT OFFICE

166,520

SHOE

Fred L. Ayers, Watertown, Mass.

Application April 19, 1951, Serial No. 14,894

Term of patent 14 years

(Cl. D7—7)

To all whom it may concern:

Be it known that I, Fred L. Ayers, a citizen of the United States, residing at Watertown, in the county of Middlesex, and State of Massachusetts, have invented a new, original, and ornamental Design for a Shoe, of which the following is a specification, reference being had to the accompanying drawings, forming part thereof.

Figure 1 is a side elevation of a shoe, showing my new design in full lines.

Figure 2 is a top plan view of the same.

Figure 3 is a rear elevation of the same.

The characteristic feature of the invention resides in the extension sole at the heel end of the shoe, and an outside backstay, the lower portion of which overlies the extension sole and

forms a thickened central portion on its upper face.

I claim:

The ornamental design for a shoe, as shown and described.

FRED L. AYERS.
